Specification for Design.

Patented July 6, 1920.

Application filed March 5, 1920. Serial No. 363,571. Term of patent 7 years.

To all whom it may concern:

Be it known that I, ADELAIDE M. PORTER, a citizen of the United States, and resident of Greenwich, county of Fairfield, State of Connecticut, have invented a new, original, and ornamental Design for a Doll, of which the following is a specification, reference being had to the accompanying drawing, forming part thereof.

The figure is a perspective view of a doll, showing my new design.

I claim:

The ornamental design for a doll, substantially as shown.

Signed at New York, county and State of New York, this 2nd day of March, 1920.

ADELAIDE M. PORTER.
